UNITED STATES PATENT OFFICE.

DABNEY LIPSCOMB ERVIN, OF COLUMBUS, MISSISSIPPI.

HASP-FASTENER

1,078,037.

Specification of Letters Patent. Patented Nov. 11, 1913.

Application filed January 9, 1913. Serial No. 741,064.

To all whom it may concern:

Be it known that I, DABNEY L. ERVIN, a citizen of the United States, residing at Columbus, in the county of Lowndes and State of Mississippi, have invented a new and useful Hasp-Fastener, of which the following is a specification.

This invention relates to a hasp fastener.

The object of the present invention is to provide an improved form of hasp in which the latch member drops into a locking position and it is impossible for the same to be shaken or jarred from a locked position.

15 A further object is to provide a hasp fastener the construction of which is extremely simple.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a view in elevation of my improved fastener. Fig. 2 is a cross sectional view thereof taken on the line 2—2. Fig. 3 is a cross sectional view thereof taken on the line 3—3. Fig. 4 is a view in elevation showing a somewhat modified form. Fig. 5 is a detail view of the catch. Fig. 6 is a perspective view of a modified form.

Referring to the drawings in which similar reference numerals designate corresponding parts throughout the several views, 1 is the strap or body portion of my improved hasp and is illustrated in Fig. 1 as being pivotally supported upon a door 2, 45 3 being the door frame or jam therefor. The strap 1 is provided at its ends with suitable pivotal supporting means therefor, in the present instance illustrated as a staple 4 fitting within a slot 5. The strap 1 is 50 provided on the remote end therefrom with the usual slot opening 6 which fits over a suitable catch staple 7, all of which is of the usual and preferred form of hasp fastener.

55 Mounted upon one end of the strap 1 adjacent the slot 6 is the casing 8, the said

casing 8 being formed with flanges 9 which space the upper surface of the said casing 8 a distance from the strap 1. The said casing is rigidly held to the strap by rivets or other suitable equivalent means 10. This casing is provided approximately centrally thereof with the slotted portion 11 which slotted portion extends approximately from the upper portion of the outer surface to the lower edge of the depending wall. It is to be understood in this connection that the casing 8 is not necessarily shell-like in form but may be solid as illustrated in Fig. 3 in which the said member is provided with the slot 11 and is further provided with a somewhat larger channel or groove therebeneath, the said channel not extending to the outer surface of the said member. Either of these constructions may be employed without departing from the spirit of my invention.

The member 8 with its grooved or slotted portion 11 provides suitable retaining means for an elbow catch 12, the same being illustrated in detail in Fig. 5. Suitable trunnions 15 are formed therewith and serve as pivots about which the elbow catch may turn. Disposed approximately at the upper edge of the arm 12 are the outstanding lugs 16, the purpose of which is to limit the pivotal movement upon the trunnions 15 when the lower portion of the arm 13 is forced into engagement with the catch staple 7. A somewhat modified form is shown in Fig. 4 in which for the portion 8 there has been substituted the two retaining lips 17-17, these lips forming suitable retaining means for the trunnions 15 of the elbow catch. 80 85 90 95

In the practical operation of my improved device the normal position which the catch will automatically assume is illustrated in Fig. 2, that is with the arm 13 in a vertical position and the arm 12 in a substantially horizontal position. Upon the placing of the strap 1 over the catch staple 7 the outer portion of the said staple contacts with one edge of the arm 13 of the catch and forces the same outward to thereby rotate the said catch about the trunnions 15. This rotation will continue until the outstanding lugs 16 contact with the upper surface of the portion 8 or 17 depending upon which form of retaining member is employed. The arm 13 will then be disposed, say, approximately at 45 degrees to

the vertical. Upon pushing the strap 1 down farther upon the retaining staple 7 as the catch cannot further rotate about the trunnions 15 the said catch will be bodily 5 forced upward within the grooved portion 11 and the various parts are so designed that the said catch will be forced upward and beyond the uppermost edge of the staple 7 after which the arm 13 will immediately rotate about the trunnion 15 into 10 a horizontal position and as the outer edge of the arm 13 is beveled the catch will immediately drop into engagement with the staple 8 substantially as illustrated in Fig. 15 2. The catch does of itself naturally stay in this position and cannot be jarred or shaken therefrom. The advantages accruing from 20 a construction of this character are readily apparent and the device constitutes an extremely desirable and useful hasp fastener.

The arm 13 is provided with the aperture 18 adjacent one end thereof through which may be placed suitable locking means, it being understood in this connection that any 25 locking device may be employed. The modified form as illustrated in Fig. 6, illustrates a construction which is also self-locking and one which is more simple in construction than the other forms as illustrated. In the 30 said modification the staple 7' is elongated so that the said staple is adapted to extend beyond the portion 1 a sufficient distance to allow the leg 13' of the catch to drop therein and to thereby effect a locking of the device.

Having thus fully disclosed the construction and operation of my improved latch or fastener, what I claim to be new and original with me is:—

1. In a hasp latch the combination with 40 a suitable plate, of a catch staple extending through a slot therein, a catch mounted for rotation and translation upon said plate adapted to engage said catch staple.

2. In a hasp latch the combination with

a suitable plate, of a catch staple extending 45 through a slot therein, an elbow catch mounted for rotation and translation upon said plate and adapted to engage said staple.

3. In a hasp latch the combination with a suitable plate, of a catch staple extending 50 through a slot therein, an elbow catch member, said catch member provided with trunnions extending outwardly therefrom, means for mounting said catch member upon said plate for rotation and translation, said catch 55 member adapted to engage said staple.

4. In a hasp latch the combination with a suitable plate provided with a slot therein, a catch staple extending through said slot, an elbow catch member provided with trunnions extending therefrom, means for rotatably mounting said catch member upon 60 said plate, means for allowing said catch member to shift transversely of said plate, said catch member adapted to engage said 65 staple.

5. In a device of the class described, a plate provided with a slotted aperture adjacent one end thereof, a bell crank catch member provided with trunnions extending 70 therefrom, said catch member provided with lugs extending therefrom adjacent one end thereof, means for mounting said catch member upon said plate, said catch member adapted to rotate in a limited manner upon 75 said trunnions, said catch lugs adapted to limit said rotation, said lugs adapted to impart a translatory motion to said catch member, said catch member adapted to engage a staple extending through said plate 80 slotted aperture.

In testimony that I claim the foregoing as my own, I have hereunto affixed my signature in the presence of two witnesses.

DABNEY LIPSCOMB ERVIN.
